VEHICLE BOGIE CONSTRUCTION

Henri Wouter Jonkhoff, Dusseldorf, Germany

Application August 28, 1934, Serial No. 741,858

10 Claims. (Cl. 280—81)

It is known to build double-axed bogies having four wheels each carried by a longitudinal arm, the said arms extending in pairs oppositely disposed, pivotally connected to the bogie body, the vertical movements of said opposite pairs of arms being controlled by a rockable laminated semi-elliptic spring, having its pivot on the bogie.

The present invention relates to a simpler construction of such bogies, and enables an economy in the material necessary in building such four-wheeled bogies, besides resulting in improved performance. In place of four wheel carrying arms only three are used, and in place of two semi-elliptic springs only one, or in effect only one, quarter-elliptic spring is used to control the movements of the three wheel carrying arms in such a way that all the four wheels are sprung independently.

In the invention the bogie body has generally an inverted U form, the closed part carrying on top a king pin and bearings to connect it pivotally to the vehicle chassis. The two depending arms of the U-body are interconnected by means of a cross pin carrying the bearings for three wheel carrying arms extending outwardly and longitudinally one in the forward and two in the opposite direction. The single arm carries at its free end a vertical bearing for an intermediary member carrying the pivots for two rockable cross members each carrying the pivots for an axle plate for the two wheels in such a way that the two wheels forming part of a parallelogram, are not only free to move vertically, independently of each other, but moreover can be steered by means of a steering lever connected to said intermediary member, which is free to swivel in regard to the wheel carrying arm. The steering lever is connected to said member pivotally in such a way that although its free end is not involved in the vertical movements of said member, still the horizontal movements of both members are always the same.

An embodiment of the invention will be described in greater detail, by way of example, with reference to the accompanying drawings wherein:—

Figure 1 is a longitudinal view of the bogie;

Figure 2 is a sectional plan view with the rear wheel-carrying arms broken away to show the quarter-elliptic spring. The latter is shown longitudinally split into two equal parts which always move together constituting, therefore, for all practical purposes, a single spring;

Figure 3 is a view showing the rear wheel-carrying arms (which are omitted in Figure 2);

Figure 4 is a front view of the forward steering wheels (on the left of Figures 1 and 2);

Figure 5 is a rear view of the two rear wheels (illustrating a geared connection hereinafter described); and

Figure 6 is a diagram showing how a vehicle body is mounted at one end on a pair of bogies disposed side by side.

Referring to the drawings in detail, A designates the bogie body which is of inverted U-shape 10 and which supports, through bearings 2, the vehicle platform or chassis designated as C, the said platform or chassis C being pivotally mounted on the body A as indicated at 1.

The two depending side portions or legs 3 of the 15 body A are connected together by a horizontally disposed cross pin 4, and on said cross pin is mounted, for vertical swinging movement, a single forwardly extending steering wheel carrying arm 5 and a pair of rearwardly extending rear wheel 20 carrying arms 6 and 6'. In this connection it will be observed by reference to Fig. 2 that the steering wheel carrying arm 5 has three spaced bearings, 7, 8 and 9, on the cross pin 4; that the legs 3 of the body A bear on said pin adjacent to the outer bearings 7 and 9 respectively, of the arm 5; that the arm 6 has a bearing 6^a on said pin between one of the legs 3 of the body A and the middle bearing 8 of the arm 5, and that the arm 6' has a bearing 6^b on said pin between the 30 other of the legs 3 of the body A and said middle bearing 8 of the arm 5. It will further be observed that the arm 5 extends rearwardly beyond the cross pin 4, as indicated at 5^a, and that on its rearward extension 5^a are mounted the forward ends of a pair of quarter-elliptical laminated springs 10, 10 which, to all intents and purposes, 35 may be considered as a single spring.

The arms 6, 6' overlie the spring or springs 10 and near their rear ends have mounted thereon, respectively, the two rear bogie wheels W. In addition, each arm 6, 6' carries near its rear end an inwardly facing gear segment 12, said gear segments being spaced apart and having interposed therebetween a pinion 13 which is 45 carried by a member 14 on which rests the rear end or ends of the spring or springs 10. Any load imposed on the bogie body A thus is transmitted yieldably to the wheels W through the spring or springs 10 and the arms 6, 6' and 50 through the pinion and gear segment connection between said spring or springs and said arms. Consequently, while the load is yieldably supported upon the wheels W, the latter obviously are free to move vertically relative to each other 55

in passing over uneven surfaces as illustrated in Fig. 5. In this connection, in order to maintain the arms 6, 6' parallel, thus to assure constant engagement of the pinion 13 with the segments 12 and a constant spaced apart relationship of the wheels W, the arms 6, 6' preferably are provided with interfitting, relatively slidably formations 11 as illustrated in Fig. 3.

On the axle 23 of each wheel W is a worm wheel 24 which is in mesh with a related worm 25 on a related shaft 26 suitably journaled on the related wheel carrying arm, while on each wheel carrying arm 6, 6' is a platform formation 27 on which is mounted a motor 28 which is connected with the related worm wheel shaft 26 to drive the same. There is thus provided a constant individual drive for each wheel W.

At the forward end of the arm 5 is a vertically disposed bearing 29 in which is rotatably mounted a vertically disposed pin 30 which extends above and below said bearing and which carries, above and below said bearing, a pair of horizontally disposed, forwardly and rearwardly extending pivot pins 31 and 32, respectively. Yokes 33 and 34 are intermediately pivoted on the pins 31 and 32, respectively, and related ends of said yokes are connected together by links or plates 35 on which are mounted the front steering wheels W, W', respectively. Said wheels thus are connected together by a parallelogram structure comprising the pivoted yokes 33 and 34 and the links or plates 35 so that any upward movement of either of said wheels relative to the arm 5 imparts an equal amount of downward movement of the other wheel relative to said arm. In other words, the wheels W, W' are free to move vertically relative to each other, one under the control of the other, and at the same time, due to the mounting of the parallelogram structure on the pin 30, the wheels are free to be rotated in a horizontal plane relative to the arm 5 for steering purposes. In this latter connection it will be observed that the upper end portion of the pin 30 is in the form of a hollow housing having side walls in which are mounted the ends of a cross pin 21, and that on said cross pin is rockably mounted a forwardly and rearwardly extending tube 22 in which is slidably, extensibly mounted a steering rod 20, this arrangement providing for constant horizontal disposition of the steering rod as is apparent.

Reference to Figure 6 will show that the invention may be applied to vehicles having two bogies arranged side by side under the vehicle chassis in such a way that four wheels are placed in a transverse row, all being free to move with their bogies under the vehicle chassis, and each pair of bogies may be interconnected so as to keep them parallel to each other under all circumstances. Moreover the four front wheels 60 are steerable in pairs on different angles and the four rear wheels are each driven by a separate motor each of which is bound to move vertically with the arm 6^a or 6^b carrying said driven wheel as is shown in Figure 1, the motor being fastened to an extension over the cross pin 4, which simplifies the transmission between the motor and the driven wheel.

I claim:—

1. A four-wheeled bogie construction comprising in combination a bogie body, a forwardly extending arm and a pair of independent rearwardly extending arms pivoted on said body, a pair of steering wheels mounted on the forwardly extending arm, and a wheel mounted on each of the rearwardly extending arms, a balancing device movably connected between the rearwardly extending arms and a quarter-elliptic laminated spring fixed to and between the forwardly extending arm and the balancing device.

2. A four-wheeled bogie construction according to claim 1 wherein the bogie body is provided with a cross pin, and the single forwardly extending arm and the pair of rearwardly extending arms have their bearings on this common cross pin.

3. A four-wheeled bogie construction according to claim 1 in which the pair of rearwardly extending arms extend beyond and overlap the axles 20 of the wheels carried by same, and the spring-carrying balancing device is connected between the overlapping ends of the said arms.

4. A four-wheeled bogie construction according to claim 1 in which the spring-carrying balancing device is furnished with a pinion, and the rearwardly extending arms are each furnished with a geared segment meshing with said pinion.

5. A bogie comprising a body rotatable about a vertical axis, a single arm extending forwardly from said body and pivoted thereto for vertical swinging movements, a pair of arms extending rearwardly from said body and pivoted thereto for vertical swinging movements, spring means between said arms resisting upward swinging movements thereof, a wheel mounted on each rearwardly extending arm, and a pair of wheels mounted on said forwardly extending arm for angular steering movements.

6. A bogie as set forth in claim 5 in which the pair of front wheels are mounted on the forwardly extending arm for angular steering movements about a vertical pivot intersecting the longitudinal axis of said arm.

7. A bogie as set forth in claim 5 in which the spring means between the arms comprises a quarter-elliptical spring fastened at its forward end to the forwardly extending arm and operatively connected at its rear end to the rearwardly extending arms.

8. A bogie as set forth in claim 5 in which the spring means comprises a pair of quarter-elliptical springs both fastened at their forward ends to the forwardly extending arm and respectively connected at their rear ends to the rearwardly extending arms.

9. A bogie as set forth in claim 5 in which the forwardly and rearwardly extending arms have a common pivotal connection with the bogie body.

10. A bogie as set forth in claim 5 in which each rearwardly extending arm carries a rack, and in which the spring means carries a pinion interposed between said racks.
